UNITED STATES PATENT OFFICE.

DANIEL BARNUM, OF NEW YORK, N. Y.

SURFACE CONDENSER.

Specification forming part of Letters Patent No. 24,087, dated May 24, 1859; Reissued October 13, 1863, No. 1,552.

To all whom it may concern:

Be it known that I, DANIEL BARNUM, of the city, county, and State of New York, have invented a new and useful Mode of 5 Constructing Tubular or Surface Condensers for Steam-Engines; and I do hereby declare the following to be a full and clear description of the same, reference being had to the accompanying drawings, and to the 10 letters of reference marked thereon, making a part of this specification.

Figure 1 is a sectional elevation of the condenser exhibiting the whole interior so plainly as scarcely to require a reference by 15 letter. Fig. 2 is an end view of the condenser with the cap, which forms one of the condensing water compartments, removed, showing the ends of the tubes in place, with the joints made, by inserting rings of india 20 rubber, or other flexible packing, within recesses, without followers, and dispensing with mechanical pressure upon a portion of packing immediately surrounding each tube so as to have its elasticity free to yield under 25 the self adjusting pressure of the water and of the vacuum, to the expansions and contractions of the tubes without slipping on the metal or breaking the joints—whereby I secure perfectly tight and yielding joints, in 30 contradistinction to slipping joints as heretofore used by Hall and others.

The nature of my invention consists in constructing my condenser with joints around each tube made of vulcanized india 35 rubber or other flexible packing in the form of rings within recesses in the condensing water compartments without followers, or in any equivalent way leaving the elasticity of the packing free to 40 yield and in combination with the self adjusting pressure of the water and the vacuum to make perfectly tight and yielding joints that will compensate the expansions and contractions in each tube sepa- 45 rately without causing the packing to slip on the metal, or in any way disturbing the perfect contact of such portions of packing and tubes as were originally brought together in making the joints tight, by which 50 means all liability of fracture or leakage from unequal expansion or contraction in the tubes is entirely obviated, and also in so proportioning the size and number of the tubes, as that their aggregate capacity shall 55 be equal to the capacity of the supply pipe—

meaning by the size—that the tube shall be so small, that the water passing through it at nearly the velocity of the current in the supply pipe, will be raised in temperature with equal rapidity, and to an equal extent 60 with the water in the spray of the jet, as ordinarily used—meaning also by the number—that the tubes shall be multiplied until there is the same capacity for the passage of the water (allowing for extra friction) as 65 shall equal the supply pipe, so that the whole volume of condensing water will pass through the exhaust steam, and through the condenser, in rapid streams, assimilating the streams in the jet—so that each portion will 70 absorb its due proportion of heat in its passage through the exhaust steam, with a facility equal to the spray of the jet, from which it differs only in the intervention of the metal, composing the tubes—and in the 75 continuance of the spray entirely through the condenser, instantly expelling the heat as fast as it is absorbed in condensing the steam. The advantage thus obtained more than compensating for the loss of time in 80 transmitting the heat through the metal.

To enable others skilled in the art to make and use my invention I remark that I first provide a case or body for my condenser as seen at A Fig. 1, having two heads, into 85 which are to be fitted loosely, a sufficient number of small tubes, of about one eighth of an inch interior diameter, and about four feet in length—to have their aggregate areas, or capacity for the passage of condensing 90 water through the body of the condenser (allowing for extra friction in the small tubes) equal the area or capacity of the supply pipe—my object being to arbitrarily divide the whole volume of condensing wa- 95 ter into a combined series of small jets or currents entirely through the body of the condenser, from one condensing water compartment to the other—each jet being suffi- 100 ciently rapid to produce friction on the metal and prevent deposits, by carrying all sedimentary matter and heat instantly out of the condenser. Thus keeping the tubes practically clean and maintaining cold and active condensing surfaces on all the tubes. 105 The joints between the tubes and the heads or tube sheets may be made with india rubber or other flexible packing applied within recesses in the condensing water compartments, dispensing with followers, as seen in 110

Fig. 2, it being my intention to leave the elasticity of the packing free to yield, and to combine it, with the self adjusting pressure of the water and with the vacuum, so as to secure their united action in making perfectly tight joints that will yield and compensate the varying lengths of the tubes without slipping. This method of making joints will enable any competent engineer to remove defective tubes and to replace them with perfect joints with facility at sea.

I have found by experiment that a stream, or column, of water of about one eighth of an inch diameter, and four feet long, passing through a tube (surrounded by exhaust steam) under a pressure of fifteen pounds to the square inch, will be raised in temperature to as high a degree as is useful in forming a vacuum—thus proving, that, the same quantity of water that is ordinarily used in the jet-condenser—when divided into streams of about one eighth of an inch in diameter—and exposed to exhaust steam in tubes four feet long—and passing through them under a velocity due to a pressure of fifteen pounds to the square inch, will secure a constant, cold and active condensing surface, and condense the same quantity of steam as in the jet condenser. The temperature of the water after passing through the tubes, shows that the heat, is absorbed with equal facility with the jet, and in addition to this, it is instantly expelled from the condenser, while the spray in the jet falls to the bottom retaining the heat, until it is removed by the slow motion of the air pump. The advantage thus obtained more than compensates for the intervention of the metal, or loss of time in the transmission of the heat through the same—showing that my condenser need not be enlarged, as compared with the jet condenser. Therefore the same rule which determines the requisite capacity for a jet condenser, and also for the injection or supply pipe, determines the same points for my condenser—and when these are determined, the requisite number of small tubes for the condenser may be known as above stated.

An examination of Fig. 1 will show that I reverse the ordinary arrangement of surface condensers. That is, I pass the water through the tubes, and condense the steam upon the out side of them. I am thus enabled to divide the condensing water into small streams, and to force them through the condenser, surrounded by the exhaust steam, in rapid currents—thus assimilating the spray of the jet, in the simultaneous exposure of the whole volume of water at its lowest temperature, in a tubular spray—securing a constant, cold and active condensing surface in all the tubes. It may be seen also that the quantity of water within the condenser at one time, is less than in the

jet condenser—and that it is not retained within it as long. Hence it follows that condensation must be equally rapid, and it is believed more efficient, in proportion as the heat is more rapidly expelled from the vacuum after condensation. I remark that this arbitrary division of the condensing water into small streams, forming a tubular spray—and passing the whole of them through the condenser in rapid currents, instantly expelling from the vacuum, the heat which is absorbed in condensing the steam, presents new, and important, features in steam condensers, securing all the advantages of the jet condenser, and at the same time avoiding all the difficulties heretofore experienced in all surface condensers. The drawing, Fig. 1, also shows the caps upon each end of the condenser, embracing the ends of all the tubes. It will of course be understood that the supply pipe is to be attached to one of these, and the delivery pipe to the other. Flanges for the exhaust pipe as well as the fresh water are shown.

The necessary pumps are of course to be furnished for supplying condensing water, as well as to remove the fresh water and air from the condenser. The size or proportion of these must conform to the power of the engine and the quantity of steam used. In this connection, I remark that I am enabled to dispense with the large air pump of the jet condenser, thus effecting an important saving in power—for, lifting the condensing water from the condenser as in the jet, necessarily involves the expenditure of a large amount of power; while the supply for my condenser may be taken in and passed out on the same level, involving no more expenditure of power than is necessary to give the water motion. In Fig. 1 also may be seen a large valve, the object of which is, to enable me to use the engine high pressure in case of accident, as well as to relieve any pressure which may occur within the condenser, tending to blow out the packing from the tubes, and also to expel the air from the engine and condenser before starting the engine. It will of course be understood that the necessary facilities for access to the tubes, either in the caps or condenser, may be had through the ordinary means of what is termed "man holes."

It should be understood that I do not intend to limit myself to the precise diameter or length of the tubes, named. Experience may prove these may be varied and yet secure efficiency in condensation in the manner herein described.

Having thus fully described the nature of my invention, and shown the method of realizing its advantages I remark, that a surface condenser possessing the convenience as to size, efficiency as to condensation, and durability in materials and construction of

the jet condenser has long been a desideratum in all condensing steam engines, but more especially for purposes of navigation. Various plans, at various times, have been essayed to produce such a condenser, but hitherto without success. In all the plans heretofore essayed, convenience has been sacrificed, in the increased size which those plans rendered necessary to accommodate the mass of tubes used, and the large quantity of water required, to submerge or cover them. Condensation in those plans also, has been sluggish and inefficient, as compared with the jet condenser, for the obvious reason, that the cold water for condensation, instead of being divided into small streams, and exposed to the exhaust steam, like the spray of the jet, or assimilating to it (as with my improvements) by simultaneously covering all parts of the tubes, and thus presenting a constant, cold and active condensing surface—is delivered into, and mixed with, the large body of water in the condenser, and already in contact with that surface, so that its temperature is raised before it reaches the tubes, and its best effects are therefore lost—no part of the condensing surface having the benefit of the water at its lowest temperature. Another reason of inefficiency of condensation in those plans may be found, in the length of time the water remains in the condenser, in contact with the tubes—affording facilities, both in time and temperature, for the deposition of sedimentary matter forming scale upon them. These difficulties are entirely obviated in my condenser in the rapid motion of the water through the tubes, affording no time for the deposition of any saline or other sedimentary matter upon the surface of the tubes—besides, the friction of the water would effectually prevent, or remove any deposits which might otherwise tend to fasten upon the metal. In nearly all those plans also, the condensers have been constructed with firm metal joints between the heads and the tubes. These have all failed from the unequal strain upon them, from the want of uniformity in the temperature of the water in the condenser in its various parts, and from the successive contractions and expansions following each exhaust of steam from the engine into the tubes, which tubes will expand or contract, more or less, in proportion as the temperature varies in the water surrounding them in those parts of the condenser, more or less, remote from the points of reception and delivery. It therefore follows that this unequal strain, and continuous action, in the metals thus brought upon the tubes, will, and does, produce fractures and leaks, and consequent failures in the result. I may add however that the arbitrary currents and equal velocities produced in my improvements, would preserve

equal temperatures in corresponding parts of each tube, and therefore the expansion would be the same in all the tubes, producing no strain upon them, except so far, as the temperature, or expansibility of the body of the condenser, might vary from that of the tubes, and consequently the durability of a condenser with metal joints would be much enhanced by my invention—in preserving equal temperatures in the tubes and relieving the strain upon them.

It should be understood that the word "spray" as used in this specification means the combined series of jets or small streams into which the whole volume of condensing water is arbitrarily divided, whether it is used in connection with my improvements, or the ordinary jet-condenser, my invention being to show a similarity between them in the simultaneous distribution of the whole of the condensing water, at its lowest temperature, and in continuous small streams or jets, to the exhaust-steam, the difference being found, mainly, in the intervention of the metal composing the tubes, which continue the jets entirely through the body of the condenser and carry the heat instantly out of the condenser and vacuum.

I am aware that Hall, Peirson and others have constructed surface condensers with clusters of small tubes—but in all cases heretofore, the condensing water space, within the body of the condenser (relatively with the supply pipe) has formed a large reservoir of water covering the tubes, the steam being condensed within the tubes, consequently the cold condensing water is delivered into, and mixed with the warm water, already in contact with the condensing surface in which its temperature and velocity—or the benefits of them are lost—hence their failure—while my success is secured by the small jets, and rapid currents, which brings each portion of the condensing water at its lowest temperature into direct contact with some portion of the metal of some one of the tubes, upon the opposite side of which the steam is being condensed. This result can not be accomplished with their arrangements for condensing the steam within the tubes or by the condensing water being applied to the outside of them. I do not therefore claim clusters of small tubes—merely as such—knowing they have been used by others, but not in the manner, or under the same arrangements, or producing the same results as are herein described and shown. Nor do I claim making a series of tubular joints, (in constructing tubular surface condensers) in one continuous sheet of india rubber packing; nor do I claim compensating joints around each tube except when made in the condensing water compartments of tubular surface condensers,

so as to leave the elasticity of the packing free to yield to the varying lengths of the tubes without slipping; nor do I claim a relief valve.

5. What I claim as my invention and which I desire to secure by Letters Patent of the United States is—

1. The method substantially as specified of making yielding joints between the tubes 10 and tube sheets in the condensing water compartments of surface condensers and of thus compensating the expansions and contraction in the tubes—by the means of leaving a portion of india rubber or other elastic packing immediately surrounding each tube free so that its elasticity can yield lon-

gitudinally with the tubes and compensate for their varying lengths without causing the packing to slip on the metal—substantially as and for the purposes specified.

2. I claim also the combination of a relief valve with yielding joints (without followers) in the condensing water compartments of surface condensers for the purpose of preventing the blowing out of the packing, and thus preserving the joints substantially as specified. 20 25
